United States Patent Office.

ASAHEL H. HUSSEY, OF MOUNT PLEASANT, OHIO.

Letters Patent No. 97,925, dated December 14, 1869.

IMPROVED HEDGE-TRIMMER.

The Schedule referred to in these Letters Patent and making part of the same.

To all whom it may concern:

Be it known that I, ASAHEL H. HUSSEY, of Mount Pleasant, in the county of Jefferson, and State of Ohio, have invented a new and useful Improved Hedge-Trimmer; and I do hereby declare that the following is a full, clear, and exact description thereof, reference being had to the accompanying drawings, in which—

Figure 1 is a front elevation, and

Figure 2, a top view.

Like letters designate like parts in all the figures.

The nature of my invention consists in the construction of a machine for trimming hedges. It being so arranged that it is readily carried and operated by one person.

To enable those skilled in the art to make and use my invention, I will proceed to describe its construction and operation.

The frame of the machine is composed of two side pieces, A A', and three cross-bars, B B B. At one side of this frame is a cutting-apparatus, similar to that used in an ordinary mowing-machine. This is hinged at its lower end to the side-piece A', as shown in fig. 1.

About midway of the finger-bar is attached a rod or bar, C, which extends through an aperture in the side-piece A'.

In this rod or bar are holes, in either one of which the pin a may be placed, thus enabling the cutting apparatus to be fixed at any desired angle.

Inside of the frame is a serpentine-grooved wheel, D, which is secured to the shaft b, whose bearings are in the side-pieces A A'. This serpentine-grooved wheel is placed on the shaft near the side-piece A.

On the outer end of this shaft b is a crank, e, by means of which, the shaft b and wheel D is revolved.

To the lower cross-bar of the frame an elbow-lever, E, is pivoted, on the upper end of which is a friction-roller, d, which fits into the groove of the wheel D, and its other end is connected to the cutting-bar F, by means of a rod, e.

Secured to the side-pieces A A', is a guard, G, which extends around back of the grooved wheel D.

H is a strap, which is secured at the same parts of these side-pieces, and is intended to pass around the back of the operator, he being between it and the guard G. This strap is made adjustable by means of a buckle or other convenient fastening.

At the upper ends of the side-pieces A A' is a strap, I, by means of which the machine is suspended from the neck and shoulders of the operator.

The machine is operated as follows:

The shaft b and grooved wheel D is caused to revolve by turning the crank e. As the wheel D revolves, the serpentine groove gives a reciprocating motion to the elbow-lever E, which imparts a like movement to the cutting-bar F, and the hedge can be trimmed as described.

Having thus fully described my invention, What I claim, and desire to secure by Letters Patent, is—

A hedge-trimmer, so constructed as to be carried by the operator, and provided with harvester-like cutters, operated by a crank, serpentine-grooved pulley, and elbow-lever, substantially as shown and described.

ASAHEL H. HUSSEY.
